A. SCHMIDT,
SPARK PLUG.
APPLICATION FILED SEPT. 25, 1918.

Patented Nov. 16, 1920.

WITNESS:

Arthur F. Draper

INVENTOR.
Albert Schmidt
ATTORNEY.

UNITED STATES PATENT OFFICE.

ALBERT SCHMIDT, OF FLINT, MICHIGAN, ASSIGNOR TO CHAMPION IGNITION COMPANY, OF FLINT, MICHIGAN, A CORPORATION OF MICHIGAN.

SPARK-PLUG.

1,358,882.

Specification of Letters Patent. Patented Nov. 16, 1920.

Application filed September 25, 1918. Serial No. 255,575.

To all whom it may concern:

Be it known that I, ALBERT SCHMIDT, a citizen of the United States, and resident of Flint, Genesee county, State of Michigan, have invented certain new and useful Improvements in Spark-Plugs, of which the following is a specification.

The invention relates to spark plugs.

One of the objects of the invention is to devise a spark plug which shall be particularly adapted for high power, high speed, internal combustion engines such as those used in airplane work, though it will be obvious that the plug is adaptable for use in any motor.

Another object of the invention is to devise a plug which shall be of simple and durable construction and inexpensive to manufacture.

Another object of the invention is to devise a plug in which the insulator elements will be protected from fracture.

Another object of the invention is to devise a plug which will effectually withstand intense heat.

Other objects will appear from the subjoined specification and claims.

The drawing shows a vertical sectional view of the spark plug.

Referring to the drawing, 10 is a shell which may be formed with any desired form of exterior such as the lower end 11 customarily threaded, and the enlarged upper end 12 adapted to receive a wrench. The shell 10 on the interior is bored out, forming the insulator chamber 13 and the reduced spark chamber 14, the section 15 between the chambers 13 and 14 being beveled as shown, and the upper ridge of the shell being reduced as at 16 for the purpose of turning inwardly to form a clamping flange for the parts as hereinafter described.

Fitting within the shell 10, and of substantially the same form is a porcelain insulator 17 having the enlarged upper portion 18 with the center recess or chamber 19 and the reduced portion 20 with the center bore 21. Gaskets 22 and 23 are provided about the top and bottom of the enlarged portion 18 of the insulator and a pressure

ring 24 formed to fit the upper surface of the insulator and bearing on the upper gasket is provided in order that the reduced flange portion 16 of the shell may be turned over onto said ring to firmly compress the same with the enlarged portion of the insulator and the gaskets to a sealed position within the shell.

A central electrode 25 is suitably secured in the insulator 17, and has the lower end 60 thereof projecting downwardly to form the sparking point 26 and the upper end thereof projecting upwardly from the inner chamber 19 of the insulator 17 and threaded at the extreme upper end thereof.

In order to insulate the upper end of the electrode 25, a sleeve or tube of mica 27 is placed thereon.

To protect the upper end of the mica-covered electrode and also to more securely 70 support the same, the dome member 28 is provided, the lower end of which firmly seats on the pressure ring 24 and about the inturned top flange of the shell, said dome member 28 being formed of an insulating 75 material and having the top center orifice 29 through which the extreme upper end of the electrode 25 extends, said electrode having a suitable washer 30 thereon next said dome and a terminal nut 31 threaded or otherwise 80 secured to the extreme top thereof as customary.

Emphasis must be made on the peculiar arrangement and form of the porcelain insulator 17, that is, it is entirely contained 85 within the shell and has a very substantial body portion firmly clamped therein and provided with proper gaskets and the special pressure ring whereby the clamping action necessary during assembly will not 90 fracture the insulator but will firmly seat the same to form a lining for the entire shell with the lower end thereof projecting downwardly into the sparking or fire chamber, and the enlarged portion recessed at 19 95 as described whereby the electrode supported by said insulator is practically only in contact therewith for a comparatively small part of the lower length of the electrode, that is, the part exposed to the fire 100

and heat of the gases of combustion. For this purpose such material as a good grade of porcelain is necessary in order to withstand the intense heat. It is further advantageous to have this part of the insulator comparatively small, or what might be termed a "stub section," so that no twisting or torsional stresses will be caused due to any extreme length thereof, and partly for this purpose the recess or chamber 19 is formed in the insulator though this chamber also permits of the mica sleeve or tube 27 extending down on the electrode whereby short circuiting is prevented between the 15 electrode and the pressure ring 24.

The arrangement of the electrode as anchored at comparatively the lower end thereof and having the upper end free from the bottom of the insulator chamber 19 permits the upper portion of the electrode to spring or move slightly with any severe vibration or shock without causing stresses upon the insulator 17 which might fracture or crack the same, and of course the electrode 25 is 20 supported by the dome member 28 as described whereby the upper end thereof will be held from any excessive movement which might be in any manner transmitted with detrimental effect to the porcelain insulator 17.

It will be obvious to those skilled in the art that many modifications and changes may be made without departing from the spirit and scope of the invention.

Having now described my invention what I claim as new and desire to secure by Letters Patent is:

1. A spark plug comprising a shell, an insulator supported within said shell, a central electrode supported in said insulator and projecting therebeyond to form a lower sparking point and an upper electrical terminal, and a tube of mica extending beyond the upper end of said insulator and covering said upper electrical terminal.
2. A spark plug comprising a shell, an insulator supported within said shell, a central electrode supported in said insulator and projecting therebeyond to form a lower sparking point and an upper electrical terminal, and a tube of mica covering said upper electrical terminal and extending beyond the upper end of said insulator, and extending also partway into said insulator.
3. A spark plug comprising a shell having an upper insulator chamber and a reduced lower sparking chamber, an insulator having a body portion secured in said insulator chamber and a reduced lower end extending into said sparking chamber and clear of the walls thereof, a central electrode anchored in said insulator and having the upper end thereof extending above the upper end of said insulator, a mica

tube around the upper end of said electrode, and a dome the lower end of which abuts against said shell and which dome incloses said tube and through which the extreme upper end of said electrode extends.

4. A spark plug comprising a shell having an upper insulator chamber and a reduced lower sparking chamber, an insulator having a body portion secured in said insulator chamber and a reduced lower end extending into said sparking chamber and clear of the walls thereof, said insulator being recessed on the upper end about said electrode, a central electrode anchored in said insulator and having the upper end thereof extending above the upper end of said insulator, a mica tube around the upper end of said electrode, and a dome the lower end of which abuts against said shell and which dome incloses said tube and through which the extreme upper end of said electrode extends.

5. A spark plug comprising a shell having an insulator chamber and a reduced sparking chamber therebelow, an insulator in said insulator chamber and the upper end of which lies below the upper end of said shell, a central electrode supported by said insulator, and a pressure ring fitting about the upper edge of said insulator and pressed thereagainst by an inwardly turned upper edge of said shell.

6. A spark plug comprising a shell, a central electrode, an insulator fitting said shell and supporting said electrode and having a beveled upper face, and the upper end of which insulator lies below the upper end of said shell, and a pressure ring fitting said insulator on the beveled face thereof and clamped therewith in said shell by an inturned upper flange.

7. A spark plug comprising a shell, a central electrode, a porcelain insulator between the lower part of said electrode and said shell and having a reduced lower end exposed to the gases of combustion, and a mica insulator covering the upper part of said electrode and extending beyond the upper end of said insulator.

8. A spark plug comprising a shell, a central electrode, a porcelain insulator between the lower part of said electrode and said shell and having a reduced lower end exposed to the gases of combustion, a mica insulator covering the upper part of said electrode, and a dome of insulating material inclosing said mica tube and the lower end of which abuts against the upper end of said shell.

9. A spark plug comprising a shell having a center chamber reduced at the lower part thereof, an insulator correspondingly formed and permanently secured in place

within said shell, and the upper end of which insulator terminates below the upper end of said shell, and an electrode supported in said insulator.

- 5 10. A spark plug comprising a shell having an internal chamber reduced at the lower end thereof, a porcelain insulator fitting within and in contact with the interior of said shell, and having a chamber 45 formed in its upper end, an electrode supported in a central bore provided in said insulator, and a mica tube surrounding said electrode and extending into said chamber in the upper end of said insulator, and which 50 15 tube extends beyond the upper end of said insulator.

11. A spark plug comprising a shell having an internal chamber reduced at the lower end thereof, an insulator fitting within and 20 in contact with the interior of said shell, an electrode supported in a central bore provided in said insulator, and a dome capping said shell and the lower end of which abuts against the upper end thereof, and through 25 which dome the extreme upper end of said electrode extends.

12. A spark plug comprising an external shell or casing having an insulator chamber within the same, and a spark chamber of 30 reduced diameter located below and communicating with said insulator chamber; an insulator fitting within and permanently secured in place in said insulator chamber and having a reduced portion extending into 35 said spark chamber, and the upper end of which insulator terminates below the upper end of said external shell or casing; a central electrode extending through a bore provided in said insulator and terminating below the lower end thereof, and the upper 40 end of which electrode extends above the upper end of said shell or casing; an insulat-

ing tube surrounding the projecting upper end of said electrode; a dome formed of insulating material surrounding said insulating tube and the lower end of which abuts against the upper end of said shell or casing and which dome is provided with a hole through which the upper end of said electrode extends; and a nut in threaded engagement with the upper end of said electrode, and which nut abuts against the upper end of said dome to thereby hold the same in place.

13. In a spark plug, an external shell or 55 casing having an insulator chamber within the same; an insulator located within said insulator chamber and permanently held in place within the same, and which insulator is provided with a recess in its upper end; a 60 central electrode extending through a bore provided in said insulator and below the lower end thereof, and extending also upwardly through said recess and beyond the upper end of said shell or casing; an insulating tube surrounding the projecting upper 65 end of said electrode and extending downwardly into said recess, and upwardly beyond the upper end of said insulator and beyond the upper end of said shell or casing; 70 a dome formed of insulating material and which dome incloses the free upper end of said insulating tube and the lower end of which abuts against the upper end of said shell or casing, which dome is provided with 75 a centrally located hole through which the upper end of said electrode extends; and a nut in threaded engagement with the upper end of said electrode and which nut abuts against the upper end of said dome to thereby hold the same in place relative to said 80 internal shell or casing.

In testimony whereof I affix my signature.
ALBERT SCHMIDT.
